UNITED STATES PATENT OFFICE.

JOHN H. HERMAN AND GEORGE W. JONES, OF NEW CASTLE, PENNSYLVANIA.

BUTTON.

Application filed December 22, 1926. Serial No. 156,383.

This invention relates to a new and useful device in the nature of a button, particularly adapted for use in connection with garments, clothing and the like.

5 The object of the invention is to provide a button which may be attached to or removed without mutilation to the garment to which same is attached.

10 A further object of the invention is to provide a button of novel construction and arrangement of parts, hereinafter more fully described, claimed and illustrated in the accompanying drawing, in which:

15 Fig. 1 shows a perspective view of our improved button.

Fig. 2 shows a bottom plan view thereof.

Fig. 3 shows a central sectional view taken on the line 3—3 of Fig. 2.

20 Fig. 4 shows a similar view to that illustrated in Fig. 3, but showing our improved button in an open or disengaged position.

Fig. 5 shows a central sectional view taken on the line 5—5 of Fig. 2.

25 Fig. 6 shows a perspective detail view of the locking member.

Fig. 7 shows a perspective detail view of the catch member.

As here embodied our improved button comprises a front plate 10 of ring shaped construction having a flanged portion 11. The back plate 12 is provided with a flanged portion 13, adapted to engage in the flanged portion 11 of the front plate 10. The flanged portion 11 of the front plate 10 is 30 provided with extended elements 14, adapted to engage in slots formed in the flanged portion 13 of the back plate 12. The above described construction being such as will attach the front plate 10 to the back plate 13.

40 The locking member 15, of circular disc construction, is positioned inside the front plate 10, below the flanged portion 13 of the back plate 12. The latter described construction being such as will permit the front plate 10 to carry or hold an ornament 16, glass, a stone or the like.

45 The catch member 17, preferably of spring steel wire or the like, is formed or bent circular and is provided with diametrical portion 18, having a central raised element 19 and a downwardly bent extremity 20.

The catch member 17 is positioned inside the back member 12, having its circular bent portion positioned under the above mentioned extended elements 14 of the front plate 10. The back plate 12 is provided with elongated slots 21, adapted to receive the diametrical portion 18 of the catch member 17. The raised portion 19 of the catch member 17 being positioned outside the back plate 12.

55 The locking member 15 is provided with extended elements 22, bent or formed parallel to the locking member 15, so as to provide hooks, adapted to receive the diametrical portion 18 of the catch member 17, when our improved button is rotated or turned. Attention is directed that the only openings to the inside of the button are the 60 slots 21, which are fairly well covered by portions of the catch member 17, and therefore, the extended elements 22 of the locking member 15 are protected from dirt, or the like, having a tendency to block the hooking 65 action thereof, rendering the device inoperative.

70 It being understood that the bent extremity 20 of the locking member 15 is forced or pushed through the garment to which our improved button is to be attached, when same is in an open position, as shown in Fig. 4 of the accompanying drawings.

Having thus described our invention, what we claim as new and desire to protect by Letters Patent of the United States is as follows:

75 1. In a garment button, the combination 80 with a front plate having a flanged portion slidably engaging over a flanged portion of a back plate provided with a movable catch member, of a locking member inside the front plate, and below the flanged portion of the back plate, extended elements formed therefrom and bent parallel to the locking member, forming hooks engageable with the movable catch to lock the catch in closed position.

90 2. In a device of the class described, the combination of a front plate having a 95 flanged portion, a back plate having a flanged portion slidably engaged within the first mentioned flanged portion, a catch member positioned inside of the back mem-

ber, and having a portion movable and extending outside of the back member, and a locking member positioned inside of the front member thereby protected from dirt, and the like, and provided with extended elements formed parallel therewith, forming hooks engageable with the movable

catch member to lock the catch in closed position.

In testimony whereof we have affixed our 10 signatures.

JOHN H. HERMAN.
GEORGE W. JONES.
